DOOR CONSTRUCTION

Howard H. Turner, Lawndale, Calif., assignor of thirty-five per cent to Joseph A. Turner, Lawndale, Calif.

Application May 11, 1944, Serial No. 535,010

2 Claims. (Cl. 160—100)

This invention relates to a door construction, and more particularly to a combination window and screen for a door.

An object of the invention is to provide novel means for mounting a roller screen that is attached to a window, the window and screen being moved across an opening in a door in such a manner that when the window is opened, the screen occupies the window frame, and when the window is closed the screen is automatically wound on a roller outside of the window opening.

Another object of the invention is to provide novel and adjustable means for mounting the screen and roller, and resulting in a simplified and more efficiently operating construction.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawing merely shows and the following description merely describes one embodiment of the invention, which is given by way of illustration or example only.

In the drawing, like reference characters designate similar parts in the several views.

Fig. 1 is a perspective view of the upper portion of a door embodying my invention.

Fig. 2 is a sectional view, on an enlarged scale, this section being taken along the line 2—2 of Fig. 1.

Fig. 3 is an elevation view, partly in section, of the parts shown in Figs. 1 and 2.

Fig. 4 is a sectional view taken along the line 4—4 of Fig. 3.

Fig. 5 is a perspective view of the roller element, shown also in Figs. 1 to 3.

Fig. 6 is a perspective view of the cover plate seen in Figs. 1 and 2, but which has been removed from the construction shown in Fig. 3.

Referring more in detail to the drawing, I show a typical door comprising a top rail 10, side stiles 11 and 12 forming a window opening 13, around the edges of which may be secured moulding strips 14, which serve to guide and frame a window 15, which is slideable upwardly and downwardly across the opening 13.

Top rail 10 is provided with a roller recess 16 and a longitudinal slot 17, which communicates between recess 16 and the window opening 13.

5 therebelow. I show a pair of roller journal blocks 20 and 21, which blocks are preferably rectangular in shape so as to be held in the end portions of recess 16, which is also rectangular in form, the journals being retained in their respective positions by the interfitting outlines thereof and of opening 16, aided by the cover plate more fully described hereinbelow. Journal blocks 20 and 21 may be of any suitable material, but for purposes of this invention may be of hard wood and formed with bearing recesses 22 and 23 respectively. A holding plate 24, rectangular in shape, is suitably secured by nails or screws to an end face of block 21, and is provided with a rectangularly-shaped slot 25, as shown in Fig. 4.

10 A screen roller 26 is rotatably positioned in the bearing recesses of journals 20 and 21, and has wound thereon a flexible screen 27, the inner end thereof being secured to the roller. Roller 26 has a tubular cavity 28, in which is positioned a windup spring 29, one end of which is secured to the roller and the other end is secured to a spring anchor member 30. Member 30 is provided with a rectangularly sectioned tongue 31, which extends through slot 25 of plate 24, anchor 30 being bearing mounted in the end of roller 26 such that the anchor member is non-rotatable when the roller is rotated to unwind or wind the screen thereon, the action being such as to provide spring 29 with rotational tension when the screen is unwound, which tension serves to re-rotate the roller and wind the screen thereon in the well understood manner.

15 The anchor 30 and journal 21 mounting is such that the left end of roller 26, together with journal 21, can be removed from recess 16 and journal 21 turned, carrying with it anchor 30 so as to provide spring 29 with whatever initial tension it is desired to have. Should it become desirable to change this tension, journal 21 can be removed and again turned to either increase or decrease this tension. Cover plate 38 covers the recess 16 and the roller and journals, and may be so shaped to retain the journals in the recess. Plate 20 38 may be secured to rail 10 as by screws 39.

25 A control lever 40 is pivoted on a screw 41, to swing between the stile 12 and the cover 38. The lever 40 has a detent 42, which in one position of the lever 40 is opposite a pin 43. The pin 43 has a round head 44. A spring 45 tends to move the head 44 to engaging position with a plate 46 on a handle 47. When the detent 42 is not in engagement with the pin 43, the plate 46 and the window 15 may be lowered, since the headed pin 43 acts as a spring catch in connection with

the flange 48 of the plate 46. However, when the lever 40 is moved to a position in which the 5 detent 42 is opposite the pin 43, movement of the head 44 to the left in Fig. 2 is thereby prevented, thus locking the window 20 in its closed position. It is to be understood that the lever 40 is on the inside of the door, so as to prevent anyone on the outside from lowering the glass and breaking through the screen 27.

Welded back to back with the plate 46 is a 10 channel-shaped member 49, provided with an inward flange 50. A clamping strip 51 for the screen 27 has a portion 52 folded upon itself. In assembling, the screen 27 is placed around the inner surface of the channel 49, and the strip 51 is 15 then forced into the channel until a strip portion 52 engages under the flange 50, thus clamping the lower end of screen 27 in the channel 25.

A U-shaped strip 53 is arranged within the handle 47 to re-enforce same. A gripping strip 20 54 engages over the top of the window 15, and is in turn engaged by a flange 55 depending from the handle 47. A resilient pad 62 is placed over the upper edge of glass 15 beneath the gripping strip 54.

Moulding 14 extends along the sides of opening 13 in the door that is automatically closed by the screen or window, or part of each. Felt strips 57 line the inner faces of the moulding 14 and the inner surfaces of slot 17. Cover plate 30 38 has a notch 61 on the inner side in which the lever 40 operates.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may 40 fall within the scope of the appended claims.

Having thus described my invention, what I claim and desire to secure by Letters Patent is:

1. In a construction of the type referred to, including side stiles and a top rail forming an opening, the combination of a slidable window for said opening, having an edge portion movable into and out of said opening and window balancing and screen means resiliently mounted in said top rail and secured to said window edge, said means including a roller for said screen, a spring within said roller and fixed therein and thereto at one end, an anchor for the other end of said spring, said anchor having a projecting tongue, journal blocks for the ends of said roller mounted in said rail, and a plate secured to the end of one of said journal blocks, said plate having a slot to accommodate the tongue of said anchor, and said journal block and plate being removable from said rail for adjustment of said spring.

2. In a construction of the type referred to including side stiles and a top rail forming an opening, said rail having a substantially rectangular opening, the combination of a slidable window for said opening having an edge portion movable into and out of said opening, and window balancing and screen means resiliently mounted in said top rail and secured to said window edge, said means including a pair of journal blocks fitting in the respective ends of the opening in said rail, a roller disposed at its ends in said journal blocks, a spring within said roller and fixedly connected at one end to said roller, an anchor for the other end of said spring provided with a tongue, a plate secured to the outside end of one of said journal blocks and provided with a slot into which said tongue extends, said block and plate being rotatable relative to the roller to provide the spring thereof with rotational tension.

HOWARD H. TURNER.
